UNITED STATES PATENT OFFICE.

EARL J. GRIGSBY, OF AKRON, OHIO.

DIRECTION-INDICATOR FOR MOTOR-VEHICLES.

1,323,049.

Specification of Letters Patent.

Patented Nov. 25, 1919.

Application filed March 27, 1918. Serial No. 225,014.

To all whom it may concern:

Be it known that I, EARL J. GRIGSBY, a citizen of the United States, residing at Akron, in the county of Summit and State 5 of Ohio, have invented certain new and useful Improvements in Direction-Indicators for Motor-Vehicles, of which the following is a specification, reference being had to the accompanying drawings.

10 This invention relates to an improved direction indicator for motor vehicles and more particularly to certain improvements in an indicator of that character shown and described in Patent No. 1,238,419 issued 15 to Edwin W. McKinley and Earl J. Grigsby on August 28, 1917.

It is the primary object of the present invention to provide improved means for operating the rotary signal carrying drum 20 and for automatically returning the drum to normal position to display the danger signal, for which purpose the usual tail lamp is provided.

It is a more particular object of the invention to provide a signaling device of the above character embodying an outer casing or housing, a signal carrying drum within the housing and an operating shaft for the drum rotatably mounted in one end of the 30 housing, a spring yieldingly holding the shaft against rotation in one direction, a cable wound on one end of said shaft, and means on the steering post of the vehicle to which the cable is connected, whereby the 35 drum may be rotated against the action of said spring to display any one of the signals carried thereby.

It is also another object of the invention to provide simple and effective means for 40 retaining the signal drum in any one of its adjusted positions and to also provide means for limiting the rotation of the drum in each direction.

And it is a further general object of my 45 invention to materially simplify and improve the construction of the patented device above referred to, and at the same time render the signal more reliable and efficient in operation and capable of manufacture 50 and application to the ordinary motor vehicle at comparatively small cost.

With the above and other objects in view, the invention consists in the improved com-

bination, construction and relative arrangement of the several parts as will be herein- 55 after more fully described, subsequently claimed and illustrated in the accompanying drawing in which similar reference characters designate corresponding parts throughout the several views, and wherein:— 60

Figure 1 is a side elevation of a motor vehicle equipped with my improved direction indicator;

Fig. 2 is a longitudinal sectional view 65 through the indicator casing and drum;

Fig. 3 is a section taken on the line 3—3 of Fig. 2;

Fig. 4 is a detail elevation of the transparent signal carrying band removed from the drum; and 70

Fig. 5 is a detail sectional view illustrating the cable winding drum which is mounted on the steering post of the vehicle.

Referring in detail to the drawing, 5 designates the casing or housing of the indicator which is preferably of cylindrical form and is provided at one end with the convex lens 6. At its other end the casing 5 is provided with a hinged door 7 affording access to the interior of said casing, said door likewise carrying a convex lens 8. 75

Within the casing 5 adjacent one end thereof, the spaced spiders 9 are arranged, each of said spiders consisting of a diametrically disposed metal bar fixed at its extremities to the casing wall. Trunnions formed on the ends of an operating shaft 10 are rotatably mounted in said spiders, one of said trunnions being provided with a rectangular socket or recess 11. Adjacent 85 to the opposite end of the casing 5, an additional spider 12 is secured therein. An adjustable bearing member 13 is centrally threaded in this spider. 90

14 designates the signal carrying drum, 95 the opposite end walls of which are of skeletonized construction, and the body wall of which is provided with a plurality of longitudinally extending slots or openings 15 therein. To one end wall of the drum, a 100 rectangular stud 16 is fixed for engagement in the socket or recess 11 formed in one end of the operating shaft 10. To the other end wall of the drum a conical stud 17 is fixed for engagement in a similarly formed recess 105 or seat in the adjustable bearing member 13.

2

By the proper adjustment of this bearing, it will readily be seen that the drum 14 may be positioned and supported for rotation with the shaft 10 within the casing 5. 5 An inwardly projecting tube or socket member 18 is fixed to one end wall of the drum to receive the plug of an electric light bulb indicated at 19. Current is supplied to the electric light bulb from batteries or any 10 other suitable source through the wires 20 which are extended through an opening in the wall of the casing 5 and are suitably connected to the contacts of the socket member 18. There is sufficient slack in the wires 15 within the casing 5 so that they may wind about the trunnion on the end of the operating shaft 10 when the drum is rotated.

To the rear side of the casing 5, a tube 21 is connected at one of its ends, said tube 20 extending longitudinally and forwardly beneath the floor of the vehicle body. Through this tube the operating cable 22 extends, said cable being attached at one of its ends to one end of the shaft 10 to be wound thereon. 25 A coil spring 23 surrounds this shaft and has one of its extremities fixed to one spider 9, and the other end thereof secured to said shaft. An annular flange or collar 24 is secured upon the shaft between this fixed 30 end of the spring and the cable 22.

The cable 22 is trained around a guide pulley 25 and extended upwardly through the vehicle floor adjacent to the steering post. A casing 26 is clamped or otherwise 35 suitably attached to one side of the steering post adjacent to the hand wheel and within this casing a spool or drum 27 is rotatably mounted, an operating handle or lever 28 being fixed to one end of the drum shaft. A 40 ratchet disk 29 is also fixed upon the shaft at one side of the drum or spool, said disk being provided on its periphery with five equi-distantly spaced teeth with which a spring pressed pin 30 is adapted to engage. 45 This pin extends radially through the peripheral wall of the casing 26 and is provided with a suitable head or button whereby it 50 may be actuated. In the cable 25 above the vehicle floor, a turn buckle or other suitable device indicated at 31 is arranged for the purpose of taking up slack in the cable.

The indicative words or characters are 55 printed, stamped or otherwise delineated upon a strip or band 32 of oiled paper or other suitable transparent material. This band at its ends is provided with suitable fastening means whereby it may be securely held in place upon the periphery of the drum 14. This band bears the words "Slow", 60 "Left", "Right" and "Stop", the latter being located at one end of the band. At the other end of the band 32 there is provided a section indicated at 33 which is colored red, while the portions of the band immediately contiguous to this section are pref-

erably colored black. This red section of the band provides a danger signal which is exposed in the normal position of the drum 15. The indicative words upon the band are printed or painted in sharply contrasting colors so that they can be easily discerned and read at some distance from the machine. The casing 5 is, of course, provided with the usual sight opening shown at 34, preferably having a panel of glass or 75 other transparent material arranged therein.

In the spider 12, a stop or bumper screw 35 is threaded, and the end of this screw is adapted for bearing engagement against the lugs 36 secured to the end wall of the 80 drum.

In the operating of my invention as above described, when it is desired to display the word "Slow" the operator turns the drum 27 by means of the crank or handle 28 until 85 one of the teeth on the ratchet disk 29 engages and has passed beyond the end of the pin 30. The cable 22 will thus be wound upon said drum and unwound from the shaft 10. In the rotation of this shaft, the 90 spring 23 is coiled and placed under tension. When the handle 28 is released, the stop pin 30 coating with the tooth of the ratchet disk 29 prevents reverse rotation of the drum 27. Thus, the drum 14 is retained in 95 position to display the word "Slow" opposite the sight opening 34 of the casing 5. In a similar manner, the words "Left", "Right" or "Stop" may be displayed and the drum held in its adjusted position to indicate to other motorists or pedestrians the purpose of the operator relative to the subsequent movements of the machine. The drum 28 is preferably of such ratio with respect to the shaft 10 that one-half a rotation 100 of said drum will transmit, through the medium of the cable, a complete rotation of the shaft, 10. When the drum is rapidly rotated from its normal position to display the word "Stop", requiring almost a complete rotation of the drum, the stop or bumper screw 35 engaging one lug 36 on the end wall of the drum, stops the rotation of the drum and indicates to the operator that the word is disposed opposite the sight 115 opening of the casing, so that he will not continue to rotate the drum 28 and thus place the cable 22 under a strain. In order to release the drum 28, the operator pulls the pin 30 outwardly, and the spring 23 will then immediately expand and reverse the rotation of the shaft 10, returning the drum 14 to its normal position and again displaying the danger signal 33 through the sight opening 34.

The casing 5 is preferably provided in its bottom portion with an opening and suitable reflecting means may also be provided to reflect light rays from the lamp 19 through said opening and upon a license 120 125 130 plate.

plate indicated at 37 which is mounted or supported in suitable means fixed to the casing wall.

From the foregoing description taken in connection with the accompanying drawing, the construction and manner of operation of my invention will be clearly and fully understood. By the provision of the single flexible cable for operating the rotatable drum of the indicator, I provide efficient and reliable means for this purpose which can be operatively applied to the ordinary motor vehicle without necessitating any alterations in the construction thereof. The several other parts of the device are also of very simple form and can be readily mounted in their operative positions by the purchaser. Thus, the device can be used in the nature of an accessory or attachment for motor vehicles. In view of the very simple construction of the various elements employed, it is also manifest that my improved direction indicator can be produced at comparatively small manufacturing cost.

While I have herein shown and described the preferred construction and arrangement of the several elements, it is to be understood that the device is susceptible of considerable modification therein and I therefore reserve the privilege of adopting all such legitimate changes as may be fairly embodied within the spirit and scope of the invention as claimed.

I claim:—

1. A signaling device for vehicles including an elongated casing having its ends transparent, a signal carrying drum rotatably supported within the casing and of a length less than the casing, the end walls of the drum being provided with openings, an illuminating member arranged within the drum, the rays thereof passing through the openings in the end walls of the drum and the transparent ends of the casing, and means for rotating the drum.

2. A signaling device for vehicles including an elongated casing having its ends transparent, a signal carrying drum rotatably supported within the casing and of a length less than the casing, the end walls of the drum being provided with openings, an illuminating member arranged within the drum and carried thereby, the rays thereof passing through the openings in the end

walls of the drum and the transparent ends of the casing, and means for rotating the drum.

3. A direction indicator for vehicles including a casing having a sight opening, the ends of the casing being provided with openings, transparent closures for said openings, a drum rotatably supported within the casing and of a length less than the casing, said drum being provided with a plurality of signals for individual exposure through the sight opening of the casing, the ends of the drum being also provided with openings, an illuminating member for the signals arranged within the drum, the rays of said member also passing through the openings in the ends of the drum and the casing, and means for rotating the casing.

4. A direction indicator for vehicles comprising an elongated casing having openings in its ends, transparent closures for said openings, said casing being also provided with a sight opening, spiders intersecting said casing, a shaft rotatably supported by and between a pair of spiders, a signal carrying drum rotatably supported by a third spider and directly supported by the shaft for rotation with said shaft, an illuminating member arranged within the drum, and means for rotating the shaft.

5. A direction indicator for vehicles comprising an elongated casing having openings in its ends, transparent closures for said openings, said casing being also provided with a sight opening, spiders intersecting said casing, a shaft rotatably supported by and between a pair of spiders, a signal carrying drum rotatably supported by a third spider and directly supported by the shaft for rotation with said shaft, an illuminating member arranged within the drum, a spiral spring encircling the shaft and secured at one end portion to the shaft and at its opposite end portion to a spider, said spring operating to rotate the shaft in one direction, and means engaged with the shaft for rotating the same in the opposite direction and placing the spiral spring under tension.

In testimony whereof I hereunto affix my signature in the presence of a witness.

EARL J. GRIGSBY.

Witness:

M. C. LYDDANE.
